UNITED STATES PATENT OFFICE

WILLIAM T. JONES, OF DETROIT, MICHIGAN, ASSIGNOR TO THE EDMUNDS & JONES MFG. CO., OF DETROIT, MICHIGAN, A CORPORATION OF MICHIGAN.

LAMP-DOOR FASTENER.

1,060,189.

Specification of Letters Patent.

Patented Apr. 29, 1913.

Application filed December 4, 1911. Serial No. 663,704.

To all whom it may concern:

Be it known that I, WILLIAM T. JONES, a citizen of the United States, residing at Detroit, in the county of Wayne, State of Michigan, have invented certain new and useful Improvements in Lamp-Door Fasteners; and I do declare the following to be a full, clear, and exact description of the invention, such as will enable others skilled in the art to which it appertains to make and use the same, reference being had to the accompanying drawings, and to the characters of reference marked thereon, which form a part of this specification:

This invention relates to lamp door fasteners especially designed for securing the doors of automobile lamps, and consists in the construction and arrangement of parts hereinafter more fully set forth and claimed. The object of the invention is to provide simple and efficient means for securely fastening the door of automobile lamps so as to obviate the rattling thereof, and at the same time to so dispose the fastener as to afford a smooth exterior for the front of the lamp. The above object is attained by the structure illustrated in the accompanying drawings, in which:

Figure 1 is a top plan partly in horizontal section of a lamp embodying my invention. Fig. 2 is a fragmentary view in section showing the position of the parts with the door of the lamp unfastened. Fig. 3 is a similar view showing the position of parts at the time of the initial engagement of the pivoted latch with the keeper in the door frame. Fig. 4 is a plan view of the latch with the actuating screw in section.

Referring to the characters of reference 1 designates the body of the lamp having a flaring forwardly extending portion 2 at the front. The door 3 carries the usual glass or lens 4, and is hinged to the body at 5 in any suitable manner. Within the frame 45 of the door is a keeper 6 for entrance of the engaging end of the latch.

Mounted upon the inner wall of the flaring portion 2 of the lamp body are the parallel ears 7 between which the latch 8 is pivoted upon a transverse pin 9 which passes through said ears and through the ears 10 struck from or formed upon the latch 8. The outer or engaging end of the latch has a bent or hooked terminal 11 for entrance

into the keeper 6 of the door frame. The 55 inner end of the latch is slotted, as shown at 12 in Fig. 4, to receive the reduced inner end 13 of an actuating screw 14 which is threaded in a tapped boss 15 on the wall of the flaring portion of the lamp body. 60 The outer end of said screw is provided with a knurled head 16 to facilitate the manipulation thereof. On the inner end of said screw is a small head 17 to prevent the screw drawing through the slot 12 in the latch 8. 65 By means of this arrangement a swiveled connection is formed between the inner end of the latch and the actuating screw.

To fasten the door the screw 14 is actuated so as to screw it inwardly through the 70 boss 15. This movement of the screw actuates the latch upon its pivot to cause the bent outer terminal thereof to enter the keeper 6 in the door frame, and draw said door forcibly into engagement with the 75 jamb on the lamp body against which it closes. By straining the screw 14, after the door shall have been fully brought into contact with the jamb, the parts may be so securely fastened as to prevent rattling and 80 obviate the possibility of the screw working loose.

To release the door the screw is actuated so as to run it outwardly through the 85 threaded boss, thereby swinging the latch on its pivot to carry it free from the keeper in the jamb of the door, as clearly shown in Fig. 2.

Because of the power exerted by the screw 14 the door may be drawn into the 90 closed position from the position shown in Fig. 3, which illustrates the initial engagement of the latch in the keeper. The running of the screw inwardly from this position will compel a further entrance of the 95 latch into the keeper, and will carry the door forcibly against the jamb.

By locating the actuating screw in the rear of the flaring portion of the body, none of the fastening parts are visible from the 100 front of the lamp.

Having thus fully set forth my invention, what I claim as new and desire to secure by Letters Patent, is:—

1. A lamp door fastener comprising a 105 pivoted latch mounted on the wall of the lamp body, a door frame having a keeper adapted to receive said latch, and a screw

threaded in the wall of the lamp body and swiveled in one end of said latch to actuate it upon its pivot to draw the other end of the latch into the keeper of the door frame.

5 2. A lamp door fastener comprising a latch pivotally mounted on the inner wall of the lamp body, said latch having a slot in its inner end, a door frame having a keeper adapted to receive the outer end of

the latch, and an actuating screw threaded 10 in the wall of the lamp body and swiveled at its outer end in the slot of said latch.

In testimony whereof, I sign this specification in the presence of two witnesses.

WILLIAM T. JONES.
